UNITED STATES PATENT OFFICE.

WM. D. THOMAS, OF MORRISTOWN, VERMONT.

IMPROVEMENT IN FURNACES.

Specification forming part of Letters Patent No. 29,925, dated September 4, 1860.

To all whom it may concern:

Be it known that I, WILLIAM D. THOMAS, of Morristown, in the county of Lamoille and State of Vermont, have invented a new and improved mode of arranging furnaces for the evaporation of saccharine juices and other substances; and I do hereby declare that the following is a full, clear, and exact description thereof.

The nature of my invention consists in surrounding three sides of the fire-place, at its upper edges, with a semi-tubular flange, so constructed that, by putting on a pan or boiler, the sides of the evaporating-pan, together with the tubular flange aforesaid, will form a flue for the passage of the hot air and gases from the fire, which are thus conducted around the sides of the evaporating-pan; and also the construction of dampers at the end of the said flues, so that a stream of cold air may be admitted to the flues whenever necessary, thus preventing the burning of the substances within the pan, and also, in case of saccharine juices, preventing them from boiling over, as they are apt to do when very near the consistency of sugar.

To enable others to make and use of my invention, I give the following description of its construction and operation, reference being had to the drawings, in which—

Figure 1 is a front elevation of furnace. Fig. 2 is a section on *x x*, and Fig. 3 a vertical section on *y y*.

I build my furnace of usual materials, and, except that it is wider at the top than the bottom, of common form. I use for the top or cover of my furnace the shallow evaporating-pan or boiler now commonly used in manufacturing maple-sugar. I build the sides of my furnace of such a size that the bottom of the evaporating-pan will rest upon them at its outer edges, and so that without the flues, hereinafter to be mentioned, when the pan is in its position, there is no escape for the gases

and heated air from the fire. At intervals on two sides of my furnace I make spout-shaped depressions at the upper edges of the sides, which extend beyond the bottom of the boiler and allow the passage of flame, gases, &c., from the fire to the flues. I place the chimney or smoke-pipe at the end of the furnace opposite to the door or other opening for putting in fuel. On the two sides and the end next to the chimney or smoke-pipe I construct the flange above mentioned, which, commencing at the upper edges of the sides of the furnace where the boiler rests upon them, first extends horizontally, and is then curved upward and backward, so that its outer edge is brought back into contact with the sides of the pan or boiler, so that when the boiler is in position, a flue is formed and connected with the chimney or smoke-pipe. I close the ends of this flue nearest the door with dampers, which may be opened or shut at pleasure.

The accompanying drawings represent a furnace constructed according to my plan without the top or evaporating-pan.

The part lettered A is the body of the furnace.

B B is the flange surmounting the sides of the furnace.

C C are the openings for the escape of the gases and smoke from the fire to the flues.

D is the aperture leading to the smoke-chimney E, and F F are the dampers, one open and the other closed.

P represents the evaporating-pan when in position for use.

What I claim, and desire to secure by Letters Patent, is—

The arrangement of the side flues and dampers relatively to the pan, as and for the purpose set forth.

WM. D. THOMAS.
